UNITED STATES PATENT OFFICE.

JAMES H. BROWN, OF DENVER, COLORADO.

DESIGN FOR A HAT.

SPECIFICATION forming part of Design No. 35,349, dated November 26, 1901.

Application filed August 28, 1901. Serial No. 73,629. Term of patent 14 years.

To all whom it may concern:

Be it known that I, JAMES H. BROWN, a citizen of the United States, residing at Denver, in the county of Arapahoe and State of Colorado, have invented and produced a new and original Design for Hats, of which the following is a specification, reference being had to the accompanying drawings, forming a part thereof.

10 Figure 1 is a side elevation, Fig. 2 a rear elevation, and Fig. 3 a front elevation, of a hat, showing my new design.

As shown in the drawings, the leading or material feature of my design consists of the 15 shape of the rim, the vizor *a* of which is curved downwardly similar to the vizor of the hat known as the "derby," while at the back the rim extends nearly the same distance as at

the front, but curves inwardly or toward the crown from a point slightly in the rear of the 20 middle of the crown and also curves upwardly and inwardly, as at *b*, at the back of the hat. The crown *c* is rounded, as shown.

Having described my invention, what I claim as new, and desire to secure by Letters 25 Patent, is—

The design for a hat, as herein shown and described.

In testimony whereof I have signed my name to this specification, in the presence of 30 two subscribing witnesses, this 12th day of August, A. D. 1901.

JAMES H. BROWN.
